 Parks-Cramer Company, Fitchburg, Mass., a
 corporation of Massachusetts

Application June 26, 1936, Serial No. 87,483

23 Claims. (Cl. 299—59)

This invention relates to an apparatus for atomizing liquids and more especially to a nozzle having orifices through which the fluids are discharged into a suitable room to produce the proper humidity.

It is a well known fact, especially in textile mills, that humidities must be maintained within a relatively narrow range in order to produce satisfactory working conditions. In order to maintain this uniform humidity conventional humidifying apparatus is commonly employed and it is with an apparatus of this type that the nozzle described in the following specification is adapted to operate.

15 The water used in such humidifying systems invariably holds in suspension certain quantities of dirt, silt and other foreign matter, which tend to deposit and accumulate in the water lines, and especially around the orifices of humidifiers. In 20 a similar way the compressed air used in such humidifying devices carries along certain quantities of water vapor and oil used in the lubrication of the air compressor.

25 When the humidifier is in active operation, there is a pronounced reduction in the pressure of the compressed air immediately before it is discharged through the humidifier outlet. This reduction in pressure so reduces the temperature of the compressed air as to cause condensation 30 of water vapor and oil vapor which are commonly present in the air. This condensation causes the precipitation of carbon, dust, or other impurities present in the air which tend to adhere to the periphery of the outlet orifice, and it is common experience in the use of such devices that these accumulations after comparatively short periods of time so decrease the flow of air as to reduce the capacity of the atomizer and eventually cause it to become inoperative.

35 Similar accumulations of impurities present in the water supply also tend to cause similar difficulties, with corresponding reduction in capacity and eventual clogging. These difficulties are the cause of frequent necessity for disassembling, 40 cleaning, reassembling and readjusting the parts of all atomizers that are in common use.

45 It is therefore an object of this invention to provide automatically operated means for maintaining such air and water orifices in clean condition by dislodging all such accumulations of sediment or other undesirable material, tending to collect in the orifices, with sufficient frequency to maintain the continued operation of the atomizer at its full capacity.

50 55 It is another object of this invention to pro-

vide means for maintaining these air and water orifices open and preventing the accumulation of sediment or other foreign particles which might be in the operating fluids from becoming lodged in the orifices and thereby obstructing the evaporative capacity of the device.

It is a further object of this invention to provide a fluid atomizing device comprising two concentric orifices arranged in a body section having a separate compartment for the atomizing fluid 10 and for the air, the fluid orifices being stationary and the compartments being separated by concave-convex flexible wall members such as synthetic rubber disks. In this form a suitable penetrating means for the fluid orifices is concentrically mounted in the rubber disks which penetrating means also penetrate the stationary orifices.

When the air pressure is applied upon the flexible wall members the central portions of 20 these members will be moved away from the orifices which will, in turn, actuate the penetrating means to cause the same to be withdrawn from the orifice. A spring normally forces the penetrating means into the orifice when no air 25 is present on the disks.

It is still another object of this invention to provide means for preventing the wasteful escape of compressed air while the atomizer is in operation. For that reason, in certain preferred forms 30 of the apparatus herein disclosed, I provide flexible diaphragms as a means for performing the desired functions of certain parts that are movable to the desired extent, but which are provided with air-tight connections of such a nature that they prevent the intermittent or continuous leakage of air which is apt to occur when pistons or other similar devices are used for such purposes.

It is still a further object of this invention to provide means for preventing the entry of air 40 under pressure to any part of the channel through which the liquid to be atomized passes on its way to the point at which atomization occurs. Leakage of air into the water supply prior to atomization tends to produce an intermittent action of the atomizer which is highly objectionable, and my apparatus is carefully designed to prevent such action.

Some of the objects of the invention having been stated, other objects will appear as the 50 description proceeds which taken in connection with the accompanying drawings, in which—

Figure 1 is a side elevation of the invention installed on a suitable column within the building;

Figure 2 is an elevation looking at the right-hand side of Figure 1;

Figure 3 is a longitudinal, sectional view taken along the line 3—3 in Figure 2;

5 Figure 4 is a longitudinal sectional plan view taken along the line 4—4 in Figure 1;

Figure 5 is a sectional view of the right-hand portion of Figure 4 but showing the parts in a position when the air pressure is not applied;

10 Figure 6 is a view looking into the right-hand end of the nozzle with the cap 47 of the apparatus and snap diaphragm 48 removed therefrom;

Figure 7 is an elevation of a modified form of 15 the invention showing the same installed;

Figure 8 is an elevation looking at the right-hand portion of Figure 7;

20 Figure 9 is a longitudinal, sectional view taken through the nozzle, along the line 9—9 in Figure 8;

Figure 10 is a longitudinal sectional plan view taken along the line 10—10 in Figure 7;

25 Figure 11 is an enlarged sectional view similar to the right-hand portion of Figure 10 showing the apparatus with the air pressure applied and the parts in operative position;

30 Figure 12 is a longitudinal sectional plan view similar to Figure 10 but showing the bellows in elevation and also showing the snap diaphragm 30 in the position occupied when no air pressure is exerted within the apparatus;

35 Figure 13 is a view looking into the right-hand end of the apparatus as shown in Figure 7 with the cap 67 of the apparatus and diaphragm 68 removed therefrom;

Figure 14 is an elevation of still another modified form of the invention showing the same installed;

40 Figure 15 is an elevation looking at the right-hand end of Figure 14;

Figure 16 is a longitudinal sectional view taken along the line 16—16 in Figure 15;

45 Figure 17 is an enlarged view of the right-hand portion of Figure 16 but showing the position which the parts occupy when the nozzle is in operation;

Figure 18 is a longitudinal sectional view similar to Figure 16 but showing certain portions thereof in elevation;

50 Figure 19 is a side elevation of still another modified form of the invention installed on a suitable support;

Figure 20 is an elevation looking at the left-hand side of Figure 19;

55 Figure 21 is a sectional view taken along line 21—21 in Figure 20 showing the penetrating means for both orifices in normal position when the air pressure is not applied;

Figure 22 is an enlarged vertical sectional view similar to Figure 21 but showing the cleaning and penetrating means in an inoperative position while the atomizing device is in operation;

60 Figure 23 is an elevation of the rubber wall portions and the associated parts on the means penetrating the fluid nozzle when the air pressure has been relieved.

65 The various constructions illustrated in the drawings disclose an atomizer head having a conduit for a liquid and a chamber for an atomizing fluid under pressure, said conduit and chamber being provided respectively with outlet elements or members one of which is resiliently actuated and arranged to permit the inner element or member to penetrate and clean the outlet of the other element or member. The atom-

izer is also provided with cleaning means for the inner element adapted to penetrate and clean the outlet thereof. Each construction is such that the respective members and elements are positioned for atomization during the continuance of the supply of atomizing fluid and that cleaning of the outlet of the outer element by penetration of the inner element and cleaning of the inner element by its cleaning means will result by relative movement of the parts between each interruption and resumption of the supply of atomizing fluid.

70 Referring more specifically to the drawings, the numeral 10 indicates a suitable column such as may occur in ordinary textile mills and to 15 which is secured a container 11 for holding suitable liquids used in spraying or humidifying the mill. This container has a float 12 pivoted therein as at 13 which rises and falls and controls the liquid level within the container by regulating the 20 amount of liquid allowed to flow into this container through inlet pipe 14. Column 10 has a suitable bracket 15 secured thereto in which is mounted an air inlet pipe 16 which leads from a suitable source of compressed air.

25 The flow of compressed air is regulated by the conventional apparatus which causes air pressure to be periodically admitted into this pipe when it is desired that the humidity in the mills be increased. Pipe 16 is secured to fitting 17 by 30 any suitable means such as collar 18 said fitting 17 being embedded into portion 20 of the apparatus.

35 Portion 20 has threadably secured therein a liquid dispensing nozzle 25 which in turn has a cavity 26 therein and an orifice 27. The cavity 26 communicates with perforations 24 which perforations also communicate with peripheral groove 28 cut in the exterior portion of nozzle 25. The liquid is drawn into groove 28 and through 40 perforations 24 from container 11 by the flow of compressed air from the air nozzle.

45 A fitting 29 is secured in portion 20 and has threadably secured thereto a collar 30 which collar securely fastens the pipe 31 in position, the pipe 31 having the lower end thereof disposed within the container 11.

50 Liquid dispensing member 25 is threadably secured in member 20 and has the left-hand threaded end thereof extending substantially beyond the left-hand edge of member 20. Threadably secured on the left-hand end of member 25 is a collar 32 which collar has one end of an expandible bellows 33 secured thereto and the other end of bellows 33 has a collar 34 secured thereto which forms an intermediate support and to which is fastened one end of bellows which is similar in all respects to bellows 33.

55 A bellows or flexible wall member 35 has its left-hand end secured to a collar 36. This collar 60 is threadably mounted on pin 37, said pin having secured thereon a piston 38 and a washer 39 which are located between the member 36 and the head portion 37a of said pin. The piston 38 is adapted to have sliding movement within a cylinder or cup member 40 which is threadably secured to portion 20.

65 It should be noted that the left-hand end of cylinder 40 is closed with the exception of a small vent hole 41 in the end thereof and mounted in 70 this cylinder and disposed between the closed end of the cylinder and the washer 39 is a compression spring 42 for normally pressing the member 37 and its associated parts to the right in Figure 4 when the air pressure is not applied to the 75

apparatus. The bellows arrangement around pin 37 prevents the liquid as it enters the nozzle from entering the air chamber, and also prevents compressed air from coming into contact with the liquid prematurely.

The right-hand end of pin 37 has a restricted portion 44 which is adapted to be pushed to the right or to the position shown in Figure 5 when there is no air pressure in the apparatus. It is evident that when this is done that any foreign particles which might have accumulated within the orifice 27 will be instantly removed.

The right-hand end of member 20 has a cap 47 threadably secured thereon and disposed between said cap and said member 20 is a snap diaphragm 48 which has a hole 49 in the central portion thereof adapted to encircle the restricted nose portion 25a of member 25, and also to coincide with a hole 52 in cap 47.

Figure 4 shows the snap diaphragm 48 when the air pressure is built up within the chamber 50 by the air which is introduced through pipe 61 and into this chamber through tangentially disposed air inlet 51. When the pressure has been built up within the chamber 50, the diaphragm 48 will bulge in snap fashion outwardly to the right as shown in Figure 4 at which time an appreciable opening will occur around the nose portion 25a to allow the air in this chamber to be emitted through this opening.

It should be noted that the air inlet 51 projects tangentially downwardly and inwardly toward the center, see Figure 6, which will cause the air to have a swirling effect as it passes through the air orifice 49 disposed around the restricted portion 25a. Air is also allowed to enter the cylinder 40 through opening 54 simultaneously with the air entering the chamber 50. When this is done the pressure within the cylinder 40 against the piston 38 will cause the spring 42 to be compressed which, in turn, will move the pin 37 to the left in Figure 4 and cause the point 44 to be withdrawn from the liquid orifice 27. Then the liquid will be drawn through the orifice 27 by the vacuum produced by the swirling blasts of air which are emitted through the hole 49 in the central portion of snap diaphragm 48.

When the swirling blasts of air are emitted around this orifice a vacuum will be created which will cause the liquid to be drawn upwardly from container 11 through pipe 31 and into the bore 26 and then outwardly through the orifice 27 where it is atomized.

There is a pronounced tendency for gum and other foreign particles to accumulate around the restricted portion 25a thus cutting down the size of the air orifice, therefore, the snap diaphragm 48 has been provided which, when not in operation, occupies the position shown in Figure 5. When the air pressure is relieved in chamber 50 this snap diaphragm 48 will snap back to the position shown in Figure 5 and at the same time the exterior portion of the nose portion 25a will be simultaneously cleansed while the orifice 27 is penetrated by the restricted portion 44.

Figures 7 to 13 inclusive show a modified form of the invention which has the bracket 60 with air inlet pipe 61 secured therein. To the upper end of pipe 61 is secured a fitting 64 by any suitable means such as collar 65, said fitting 64 being secured to the portion 66 of the apparatus. The right-hand end of portion 66 has a cap member 67 threadably secured thereon and between this cap and portion 66 is confined a snap diaphragm 68 having a hole 72 therein.

The cap member has an opening 69 in the central portion thereof which is in direct alinement with the hole 72 in the central portion of snap diaphragm 68. In other words, the hole 72 in the central portion of the snap diaphragm 68 is concentric with the hole 69 in the central portion of cap 67. This member 66 has a chamber 70 therein into which air pressure is admitted from pipe 61 through air inlet 71. This inlet progresses downwardly and inwardly, see Figures 10, 11, 12, 13, to cause swirling blasts of air within the chamber 70 in a similar manner to the inlet 51 shown and described with relation to Figure 6.

Mounted in the central portion of member 66 is a liquid dispensing member 75 which has a peripheral groove 76 cut in the exterior portion thereof which groove communicates with perforations 77 to allow the liquid to be drawn inwardly to the central portion of nozzle member 75 into bore 78 and expelled therefrom through orifice 79. The liquid is allowed to enter into groove 76 through pipe 80 which is threadably secured to fitting 81 by means of collar 82.

The left-hand end of member 75 is threaded and has secured thereon a collar 86, which collar 86 in turn has secured to the periphery thereof a flexible wall member such as an expansible bellows 87, said bellows 87 having its other end secured to another collar 88. The collar 88 is threadably secured to the threaded portion of pin 89, which pin has a washer 90 thereon which is disposed between the collar 88 and said head portion.

The extreme left-hand end of pin 89 has a snap diaphragm 91 secured thereon by means of suitable nuts 93 and 94 disposed on each side of the diaphragm and which are also threadably secured on the end of said pin. This diaphragm is held in position against the member 66 by means of a suitable cap 97 which is threadably secured on the left-hand end of member 66. This cap has a bore 98 in the central portion thereof, said bore having a vent hole 99 therein for allowing the air to enter and escape therefrom when the diaphragm 91 is actuated from the position shown in Figure 12 to the position shown in Figure 10.

A compression spring 100 is mounted in said bore 98 and has the right-hand end thereof normally engaging the nut 94 to maintain the diaphragm in the position shown in Figure 12 when no air pressure is present in chamber 102. When the air pressure is set up in pipe 61 it flows into a chamber 102 through an inlet 103 and exerts pressure against the diaphragm 91 to cause it to snap outwardly to the position shown in Figure 10. When this is done the pin 89 will be moved to the left to cause the point on the extreme right-hand end thereof to be withdrawn from the orifice 79 to allow the liquid to be drawn therefrom.

Simultaneously with the snapping of the diaphragm 91 the pressure will be set up in the chamber 70 to likewise cause the diaphragm 68 to be snapped outwardly from the position shown in Figure 12 to the position shown in Figure 11. This will allow an appreciable opening around the nose or tip of member 75 and the opening in the central portion of diaphragm 68 through which the air will be forced.

The swift, swirling movement caused by the expulsion of the air around the nozzle of member 75 will create a vacuum at this point thereby drawing the liquid from the container 11 upwardly into the bore 78 and out through the orifice 79.

When the pressure is cut off, the diaphragms 68 and 91 will return to normal position, that is,

to the position shown in Figure 12 at which time the point 89a will penetrate the orifice 79 and at the same time the opening in the central portion of the diaphragm 68 will move backwardly around the nose portion of member 75 to remove any particles or foreign matter therefrom.

Figures 14 to 18 inclusive show another modified form of the invention in which the bracket 105 has secured therein an air inlet pipe 106, said pipe being secured to fitting 107 by any suitable means such as a collar 108. The fitting 107 is secured in member 109 and furnishes means for introducing the air into the interior of the apparatus as at 110.

15 A liquid inlet pipe 112 is secured to the left-hand end of member 109 by means of a collar 113. The projection 114, which is integral with member 109, has a threaded bore 117 on the interior thereof in which is threadably mounted a pin 115, said pin 115 having a bore 116 therein which communicates with pipe 112 to allow the liquid to enter into bore 117.

Bore 117 has slidably mounted therein a tubular member 119 which is also slidably mounted 25 in a nut 120. The nut 120 is threadably secured in the right-hand portion of member 109 and has secured to the right-hand end thereof a bellows 121, said bellows 121 having its other end secured to a head portion 122 of tubular member 119.

30 The tubular member has a restricted nose portion 124 on the right-hand end thereof having an orifice 123 therein through which the liquid is adapted to be expelled (Fig. 17). When the liquid enters into the bore 117 from the pipe 112 it passes 35 between the pin 115 and the interior of tubular member 119 and then to the orifice 123.

The restricted nose portion 124 has threadably secured thereon a nut 127 which nut has secured to one side thereof a bellows 128 having flexible 40 walls. This bellows has its other end secured to a washer 129 and this washer is held in contact with the right-hand portion of member 109 by suitable means such as a flange 126 on the inside of a cup or cylindrical member 130 which is 45 threadably secured to member 109.

50 In order to allow for the expansion and contraction of the bellows 128 within the member 130 a vent hole 131 is provided. The air enters through the pipe 106 and into the interior of the apparatus through the inlet 110. It then passes into the interior of bellows 128 and on the exterior of bellows 121 and thence through an opening 133 into a peripheral groove 134 cut in the nose portion 124.

55 It will be seen by referring to Figure 18 that the peripheral groove 134 has communicating therewith a plurality of spirally disposed grooves 135 which are cut in this nose portion 124. From the groove 134 the air passes through the grooves 60 135 and is expelled through orifice 136 in the central portion of the right-hand end of member 130.

When there is no air pressure within the apparatus the parts assume the position shown in 65 Figures 16 and 18. It will be noted in this position that the extreme right-hand end of nose 124 is a substantial distance away from the orifice 136. When the air enters the inlet 110 the bellows 121 and 128 are expanded, thereby forcing 70 the orifice 123, which is in the right-hand end of nose 124, to the position shown in Fig. 17, in which position the nose 124 penetrates and cleans the orifice 136.

75 There is an appreciable clearance between the nose portion of the orifice 123 and the orifice

136 around which the air is expelled in swirling blasts, which blasts are caused to swirl by virtue of the spiralled grooves 135 cut in the nose portion. The pressure set up within the bellows 128 is sufficient to overcome the compression of a 5 spring 140 which is mounted between the right-hand side of nut 127 and the interior end portion of cylinder 130. Therefore, the right-hand restricted portion of nut 127 will be forced inwardly into a cavity or bore 142 and the restricted 10 portion 115a of pin 115 will remain in stationary position while the nose portion 124 will move to the right to cause the orifice 123 to be moved beyond the end portion 115—A of the pin 115 so that the 15 liquid will be drawn therefrom by virtue of the air 20 vacuum produced by the swirling blasts of which are emitted from the orifice 123 around the nose portion of the orifice. It is evident that when the pressure is relieved within the bellows 128 that the compression spring 140 will move 25 the parts back to the position shown in Figures 16 and 18 which will cause the point 115a to penetrate the orifice 123 to remove any foreign particles which might have accumulated therein. 25

Figures 19 to 23 inclusive show still another modified form of the invention in which a pair of resilient concavo-convex resilient disks such as rubber are used instead of a bellows in order to operate the means for penetrating the fluid 30 nozzle. This form has the particular advantage of being very simple in construction and eliminates the necessity for providing a vent hole as shown in the previous figures, and also insures 35 against leakage of compressed air. 35

The operability of this structure is dependent upon a pair of suitable concavo-convex rubber 40 wall members or disks whose peripheries are clamped in spaced relation to each other in such a manner that when air is introduced between the 45 disks that the central portions thereof will be caused to bulge or snap and operate the cleansing means for the stationary fluid orifice.

It is evident that if suitable oil resisting resilient material can be obtained for forming these 45 portions the air and liquid chambers can be separated with little probability of a leakage therebetween. The construction of a bellows that will not leak after continued use, is a very difficult task, especially if the conservation of space is 50 an important item; therefore where suitable material can be found two small rubber disks are inserted in lieu of the bellows.

In this form a suitable bracket 150 is secured to 55 post 10 which bracket supports an air inlet pipe 151. This pipe is connected at its upper end to a pipe 153 by any suitable means such as a fitting 152. The pipe 153 supports a body 154 which body has a pair of holes 155 and 156 communicating with the pipe for conducting air to the compartments 157 and 158 respectively. 60

The body 154 has a suitable liquid nozzle 160 threadably secured therein, said nozzle having a bore 161 in the central portion thereof through which the liquid is adapted to flow and be 65 atomized as at orifice 163 by the air which is expelled around the nozzle through the air orifice 164. The air orifice 164 is disposed in the central portion of snap diaphragm 165. Said snap diaphragm being held in position on the 70 right-hand end of body 154 by any suitable means such as a cap 166 which is threadably secured on the body, said cap having a hole 167 in the central portion thereof.

The construction of the right-hand end of the 75

device is very similar to the form shown in Figures 1 to 6 inclusive, and a further description is not deemed necessary at this time.

A suitable pin or plunger 170 is threadably secured in the right-hand end of member 171, said member 171 having mounted thereon resilient concavo-convex diaphragms 172 and 173. These diaphragms are circular in construction and are mounted in a suitable bore 174 in the left-hand 10 end of the body 154 as shown in Figures 21 and 22. They are preferably of rubber and are so molded as to have a tendency to move to the position shown in Figure 2. The diaphragm 172 has one edge thereof pressed against a suitable 15 shoulder 174a in the bore 174 in the left-hand end of body 154 and resting upon the opposed side of the diaphragm is a suitable spacer ring 175. This ring 175 is inserted between the proximate 20 surfaces of the rubber diaphragms 172 and 173. Since the ring has an enlarged opening in its 25 central portion, a suitable space for an air compartment 157 is provided. Adjacent the left-hand edge of diaphragm 173 is a washer 177 against which the cap 178 is adapted to rest when the cap is threadably secured in the left-hand end 30 of body 154 for closing bore 174. It is to be observed that disk 172 has less surface exposed to compressed air than disk 173. This causes compressed air between the rubber disks or diaphragms to move the assembly carrying the pin 161 to the left in Figure 22 against the force exerted by spring 186.

It is thus seen that the peripheries of the concavo-convex diaphragms 172 and 173 are held 35 in stationary position.

It will be further noted by referring to Figures 21 and 22 that the member 171 is concentrically mounted within the diaphragms 172 and 173. The member is held therein by any suitable 40 means such as by having a suitable washer 180 disposed between the diaphragms and around member 171. Another washer 181 is placed around the member 171 and is pressed against the left-hand central portion of diaphragm 173. Against this washer a nut 182 is threadably secured on the member 171 to normally press the parts in an assembled position against the enlarged head portion 171a which is integral with member 171.

The cap 178 has a bore 185 therein in which is 50 mounted a suitable compression spring 186, said compression spring encircling the left-hand end of member 171 and having its right-hand end normally pressing against nut 182 to normally press the parts to the position shown in Figure 21. Communicating with this bore is a supply pipe 189 which has its lower end extending downwardly 55 into container 11.

The liquid is allowed to center the bore 185 through the opening 188 from whence it passes 60 into the bore 190 disposed in the central portion of member 171. From the bore 190 the liquid is drawn through openings 192 into chamber 174 and then into bore 161 to the orifice 163 where it is atomized by the air which is being expelled 65 from chamber 158 through the concentric air orifice 164. The air which is expelled through the orifice 164 around the end of orifice 163 creates a vacuum and draws the liquid through the various bores previously described.

When the air pressure is applied to the apparatus the air passes through the bore 155, through a hole 172a in diaphragm 172, and then 70 through a hole 175a in ring 175 into compartment 157 to cause the pressure to bulge the diaphragm 75 to the position shown in Figure 22 which in turn

will withdraw the point of member 170 from the orifice 163. At this time, spring 186 will be compressed and the water will be drawn through the orifice 163. Simultaneously with this operation the snap diaphragm will move to the position shown in Figure 22 under the air pressure in chamber 158. When the air is released the parts will assume the position shown in Figure 21 under the pressure of the spring 186.

It is thus seen, by this arrangement that it is 10 impossible for the liquid to enter into the air compartment 157 at any time since all joints in the compartment are tightly sealed.

As has been stated, the material of which members 172 and 173 are made is preferably of 15 synthetic rubber which will resist the effect of oil, since oil is very often present in an atomizing fluid. It is possible to obtain the snap action necessary for the operation of the plunger 170 without damaging the rubber or the diaphragm, even if the central portion of the diaphragms 172 and 173 are bulged about a very sharp radius, thereby making it possible to make 20 small diaphragms and decrease the size of the body 154.

In the drawings and specification there has 25 been set forth a preferred embodiment of the invention, and although specific terms are employed, they are used in a generic and descriptive sense only, and not for purposes of limitation, 30 the scope of the invention being set forth in the appended claims.

1. A self-cleaning atomizer comprising a casing having a liquid conduit provided with a nozzle and a chamber for an atomizing fluid under pressure surrounding said nozzle and having a movable terminal wall provided with an outlet coaxial with said nozzle and normally positioned to cause its outlet to be penetrated by said nozzle but moved into proper atomizing position relatively to 35 said nozzle outlet by the pressure of the atomizing fluid.

2. A self-cleaning atomizer comprising a casing having a liquid conduit provided with a nozzle and a chamber for an atomizing fluid under pressure surrounding said nozzle and having a movable terminal wall provided with an outlet coaxial with said nozzle and normally positioned to cause its outlet to be penetrated by said nozzle, but moved into proper atomizing position 40 relatively to said nozzle by the pressure of the atomizing fluid, a cleaning member positioned in said nozzle, resilient means normally causing said cleaning member to penetrate and clean the outlet of said nozzle, and means operated by the 45 pressure of said atomizing fluid to effect separation of said cleaning member from the outlet of said nozzle.

3. A self-cleaning atomizer comprising a liquid conduit having a nozzle, a conduit for air under pressure including a chamber surrounding said nozzle provided with a movable terminal wall member having an outlet coaxial with and normally penetrated and closed by said nozzle in the absence of air pressure, said terminal wall member being moved by air pressure when supplied to said air conduit to such a position relative to 50 said nozzle as to effect atomizing discharge of the liquid, and cleaning means arranged to penetrate and clean said nozzle outlet upon release 55 of said air pressure.

4. A self-cleaning atomizer comprising a liquid conduit having a nozzle, a conduit for air under pressure including a chamber surrounding said nozzle provided with a movable terminal wall 55

member having an outlet coaxial with and normally penetrated and closed by said nozzle in the absence of air pressure, and nozzle cleaning means independent of the movement of said terminal wall, located axially within said nozzle, normally penetrating and closing the outlet thereof in the absence of air pressure, the pressure of said air when admitted to said chamber being effective to cause such separation between said movable terminal wall member and said nozzle and between said nozzle and said independent cleaning means as to produce effective atomization of the liquid by said air under pressure.

5. A self-cleaning atomizer comprising a conduit for liquid and a conduit for air under pressure having coaxially disposed outlets, the outlet for said air under pressure being provided in a movable wall member actuated by said air under pressure to effect the relative positioning of 10 said outlets in atomizing relation, the outlet for said liquid being provided in a nozzle which in the absence of said air pressure penetrates and cleans the outlet for air, and additional cleaning means for said outlet for liquid which, in the 15 absence of said air pressure, penetrates and cleans the outlet for liquid and which, when said air pressure is acting, is in non-penetrating relation to said outlet for liquid.

6. Atomizing apparatus comprising a casing 30 having an air chamber and a bellows chamber, a liquid nozzle mounted in said air chamber and having a discharge outlet, a snap diaphragm closing said air chamber upon reduction of air pressure in said air chamber and having an orifice 35 therein serving as an air nozzle upon increase of air pressure and, occupying a position where the liquid nozzle projects into said orifice, a liquid conducting pipe communicating with the interior of said liquid nozzle, a compressed air conducting 40 pipe having communication with said air chamber and said bellows chamber, a slideable plunger mounted in said liquid nozzle and projecting into said bellows chamber, means acting upon reduction of air pressure in said bellows chamber for 45 moving said plunger into the discharge outlet of said liquid nozzle, a bellows surrounding the portion of said plunger which is disposed within the bellows chamber and having one end secured to the plunger and the other end secured to the 50 casing, a diaphragm dividing the bellows casing into two compartments and being secured to the plunger whereby, an increase of air pressure in said chambers will serve to snap the first-named diaphragm to move it from contact with the liquid nozzle and also to move the plunger from the discharge outlet of said liquid nozzle.

7. A liquid atomizer comprising a tubular liquid nozzle connected to a supply of liquid, an air chamber coaxially surrounding said liquid nozzle 60 and connected to a supply of air under pressure, a snap-action diaphragm composed of resilient material disposed coaxially with, and constituting the outer wall of said air chamber, said diaphragm having a central aperture and being subject to an initial warp operable normally to close 65 said aperture by registration thereof upon the outer surface of said liquid nozzle, said diaphragm being operated to provide an outlet for air from said chamber through said aperture by distortion of said diaphragm in response to a predetermined air pressure in said chamber, a slideable plunger normally penetrating the bore of said liquid nozzle, said plunger being operated by means responsive to said predetermined air pressure, to be withdrawn from the bore of said liquid 70

nozzle in combination operable to maintain continuous atomization only during the prevalence of said predetermined air pressure.

8. Atomizing apparatus comprising a liquid nozzle having an air chamber surrounding the same and terminating at its outer end in a centrally apertured flexible diaphragm of resilient material and having an initial inward warp, acting normally to engage the periphery of said aperture with the outer surface of said liquid nozzle, a conduit for air under pressure communicating with said air chamber, a conduit for liquid communicating with said nozzle, a plunger 10 slidably mounted in said nozzle, an extensible bellows surrounding a portion of said plunger and secured by air-tight joints at its inner end to said plunger and at its outer end to said liquid nozzle, a piston mounted at its inner end on said plunger, a cylindrical casing secured at its outer end to said liquid nozzle and extending inwardly therefrom to enclose said bellows and to supply sliding contact with said piston, said casing also having internal communication with said compressed air conduit, and spring means acting normally to force said plunger outwardly to penetrate said fluid nozzle operating in response to a predetermined air pressure to force said diaphragm outward to present an outlet for said air from said air chamber and to withdraw said plunger from said liquid nozzle thereby to maintain continuous atomization in response to said air pressure and to discontinue said atomization upon interruption of said air supply.

9. A self-cleaning atomizer comprising a casing having a liquid conduit provided with a nozzle and a chamber for an atomizing fluid under pressure surrounding said nozzle having an elastically yieldable wall provided with an outlet normally penetrated by said nozzle, but moved into proper atomizing relation thereto by the pressure 35 of said atomizing fluid, cleaning means normally positioned to penetrate the outlet of said nozzle, and means operated by the pressure of said atomizing fluid to retract said cleaning means from said liquid nozzle to permit delivery of liquid 40 therefrom.

10. A self-cleaning atomizer comprising a casing having a liquid conduit provided with a nozzle and a chamber for an atomizing fluid under pressure surrounding said nozzle having a thin 50 snap diaphragm provided with an outlet coaxial with said nozzle and normally distorted to cause its outlet to be penetrated by said nozzle, but moved into proper atomizing position relatively to said nozzle outlet by the fluid pressure of the 55 atomizing fluid.

11. A self-cleaning atomizer comprising a casing having a liquid conduit provided with a nozzle and a chamber for an atomizing fluid under pressure surrounding said nozzle and having a snap diaphragm provided with an outlet coaxial with said nozzle and normally distorted to cause its outlet to be penetrated by said nozzle, but moved into proper atomizing position relatively to 60 said nozzle outlet by the fluid pressure of the 65 atomizing fluid, a plunger reciprocably mounted in said nozzle, resilient means normally causing said plunger to penetrate and clean the outlet of said nozzle, and means operated by the pressure of said atomizing fluid to retract said plunger 70 from the outlet of said nozzle.

12. A self-cleaning atomizer comprising a casing having a delivery chamber for an atomizing fluid under pressure and a pressure chamber, means for supplying fluid under pressure to said 75

- chambers, a liquid conduit mounted in said casing having a nozzle projecting into said delivery chamber, means for supplying liquid to said nozzle, a snap diaphragm in said delivery chamber 5 having an outlet in axial alinement with said nozzle and normally distorted to cause its outlet to be penetrated by said nozzle but moved by the pressure of the atomizing fluid into proper atomizing relation to said nozzle, a plunger reciprocably mounted in said conduit having an end portion adapted to penetrate the nozzle outlet, resilient means acting upon the other end of said plunger normally causing said plunger to penetrate the nozzle outlet and operated by the pressure 10 of the atomizing fluid when admitted to said pressure chamber to retract said plunger from nozzle-penetrating position.
13. A self-cleaning atomizer comprising a casting having a delivery chamber for an atomizing fluid under pressure and a pressure chamber, means for supplying fluid under pressure to said chambers, a liquid conduit mounted in said casting having a nozzle projecting into said delivery chamber, means for supplying liquid to said nozzle, a snap diaphragm in said delivery chamber having an outlet and normally distorted to cause its outlet to be penetrated by said nozzle, but moved by the pressure of the atomizing fluid into proper atomizing relation to said nozzle, a plunger reciprocably mounted in said conduit having an end portion adapted to penetrate the nozzle outlet, resilient means normally causing said plunger to penetrate the nozzle outlet, plunger-actuating means in said pressure chamber operated by the pressure of the atomizing fluid when admitted to said pressure chamber to retract said plunger from nozzle penetrating position, and impervious flexible means connected to said plunger-actuating means for preventing the atomizing fluid from entering said liquid conduit.
14. A self-cleaning atomizer comprising a casting having a delivery chamber for an atomizing fluid under pressure and a pressure chamber, means for supplying fluid under pressure to said chambers, a liquid conduit mounted in said casting having a nozzle projecting into said delivery chamber, means for supplying liquid to said nozzle, a snap diaphragm in said delivery chamber having an outlet and normally distorted to cause its outlet to be penetrated by said nozzle, but moved by the pressure of the atomizing fluid into proper atomizing relation to said nozzle, a plunger reciprocably mounted in said conduit having an end portion adapted to penetrate the nozzle outlet, a spring acting upon the other end of said plunger normally causing said plunger to penetrate said nozzle outlet, and a snap diaphragm of resilient material intermediate of said spring and said plunger operated by the pressure of the atomizing fluid when admitted to said pressure chamber suddenly to retract said plunger from nozzle-penetrating position.
15. A self-cleaning atomizer comprising a casting having a delivery chamber for an atomizing fluid under pressure and a pressure chamber, means for supplying fluid under pressure to said chambers, a liquid conduit mounted in said casting having a nozzle projecting into said delivery chamber, means for supplying liquid to said nozzle, a snap diaphragm in said delivery chamber having an outlet and normally distorted to cause its outlet to be penetrated by said nozzle, but moved by the pressure of the atomizing fluid into proper atomizing relation to said nozzle, a plunger reciprocably mounted in said conduit having an
- end portion adapted to penetrate the nozzle outlet, a spring acting upon the other end of said plunger normally causing said plunger to penetrate said nozzle outlet, a snap diaphragm of resilient material intermediate of said spring and said plunger operated by the pressure of the atomizing fluid when admitted to said pressure chamber suddenly to retract said plunger from nozzle-penetrating position, and a bellows in said pressure chamber secured to and enclosing said plunger for preventing the atomizing fluid from entering the liquid conduit.
16. A self-cleaning atomizer comprising a tubular liquid nozzle connected with a supply of liquid, an air chamber coaxially surrounding said liquid nozzle and connected to a supply of air under pressure, a snap diaphragm composed of resilient material disposed coaxially with and constituting the terminal wall of said air chamber, said diaphragm having a central aperture 20 and being subject to an initial warp operable normally to close said aperture by registration thereof upon the outer surface of said liquid nozzle, said diaphragm being operated in response to air pressure within said chamber when rising to a predetermined value to provide an outlet for said air through said aperture by distortion of said diaphragm, a slideable plunger normally occupying the bore of said liquid nozzle and means connected therewith operated only responsive to said air pressure when rising to said predetermined value to withdraw said plunger from the bore of said liquid nozzle, in combination operable to maintain continuous atomization only during the continuance of said predetermined air pressure.
17. A self-cleaning atomizer comprising a tubular member having an outlet for liquid supplied thereto, an annular chamber coaxially surrounding said liquid outlet, and having a movable terminal wall member provided with an outlet for air and operable in the absence of air pressure to maintain closure of said air outlet by registration thereof with the outer surface of said liquid outlet, cleaning means slideable axially within said tubular member operable normally to occupy and close the outlet thereof and means operated responsive to the pressure of air when supplied to said chamber to withdraw said cleaning means from said liquid outlet and to cause separation of said liquid outlet and said air outlet in combination operable to maintain continuous atomizing operation only during the maintenance of a predetermined air pressure in said chamber.
18. A self-cleaning atomizer comprising a tubular liquid nozzle surrounded by an air chamber having an annular terminal wall member provided with an air outlet coaxial with said liquid nozzle and normally closed by registration therewith, said terminal member being operated to separate said air outlet from said liquid nozzle only during the presence of air under pressure in said chamber and movable means normally operable to penetrate the bore of said liquid nozzle from within and operated only upon the admission of air under pressure to said chamber to be withdrawn from the bore of said liquid nozzle.
19. A self-cleaning atomizer comprising a nozzle for the discharge of liquid connected to a supply thereof, a chamber connected with a supply of air under pressure surrounding said liquid nozzle and terminating in a resilient closure member provided with an outlet orifice con-

- 5 centric with said liquid nozzle and normally closed forcibly by engagement therewith, said closure member being operated to cause separation of said orifice from said liquid nozzle only in response to the pressure of air when supplied to said chamber, axially slidable cleaning means operable normally to occupy the bore of said liquid nozzle by forcible penetration thereof, and means operated only by the pressure of air when supplied to said chamber to forcibly withdraw said slidable means from the bore of said liquid nozzle in combination operable to cause forcible displacement of foreign matter from said orifice and from the bore of said liquid nozzle upon each interruption of the supply of air to said chamber.
- 10 20. A self-cleaning atomizer, a chamber operatively connected with a supply of compressed air and terminating in a closure member composed of resilient material subject to an initial warp and provided with a central outlet orifice, a nozzle for the discharge of liquid operatively connected with a supply thereof and disposed within and coaxially of said chamber with the outlet of said nozzle operable normally to penetrate and forcibly close said orifice against the resilient resistance due to said warp in said closure member and operated only in response to the continuous supply of said compressed air to
- 15 30 open said outlet orifice for the escape of air from said chamber by displacement of said resilient member, movable cleaning means operable normally to forcibly penetrate and close the bore of said liquid nozzle and means secured to said movable means operated only responsive to the continuous supply of said compressed air to withdraw said movable means from the bore of said nozzle, in combination operable to maintain continuous atomization by the aspirating
- 25 35 40 action of said escaping air during the continuous supply thereof and to discontinue said atomization and clean said orifice and the bore of said nozzle upon interruption of said supply of air.
- 45 21. A self-cleaning atomizer comprising three coaxial members, two of which are relatively and independently movable, one of said coaxial members having a circular outlet aperture for
- 5 fluid, another having a tubular extension surrounding an outlet for liquid and another having cleaning means for penetrating said liquid outlet, the said members being relatively positioned by the pressure of the fluid for atomization of liquid while supplied with fluid under pressure, and means actuated by changes in the pressure of the atomizing fluid incident to interruption of the supply thereof to cause said tubular extension to pass through and clean said fluid outlet and to cause said penetrating means to pass through and clean said liquid outlet.
